UNITED STATES PATENT OFFICE.

ANTONIOS J. MURZICOS, OF GREENVILLE, TEXAS.

ICE SHAVER.

Application filed February 26, 1920. Serial No. 361,371.

To all whom it may concern:

Be it known that I, ANTONIOS J. MURZICOS, a citizen of the United States, residing at Greenville, in the county of Hunt and State 5 of Texas, have invented certain new and useful Improvements in an Ice Shaver, of which the following is a specification.

My invention relates to new and useful improvements in an ice shaver and has for its 10 principal object the construction of a device adapted to shave ice for use in drug stores or like places.

Another object of the invention consists in the provision of a slidable carriage for the 15 ice said carriage adapted to be moved longitudinally of a frame which carries the cutters for shaving the ice.

A further object of the invention consists 20 in the construction of a frame in such a manner as to discharge the shaved ice into a bucket or other suitable receptacle.

A still further object of the invention consists in means for connecting the slidable ice carriage to the frame and means for disconnecting the ice carriage so that it may be 25 carried from place to place.

With these and other objects in view my invention consists in the novel details of construction and arrangement of parts which 30 will be more clearly understood from the following specification and drawings in which:—

Figure 1 is a side elevation.

Figure 2 is an end view of one end of 35 the machine.

Figure 3 is an end view of the opposite end of the machine.

Figure 4 is a longitudinal vertical section on the line 4—4 of Figure 2.

Figure 5 is a section on the line 5—5 of 40 Figure 4 looking in the direction of the arrows and,

Figure 6 is a fragmentary sectional detail 45 showing the manner of mounting the follower in the slidable carriage.

In carrying out my invention I provide a supporting frame indicated generally at A and a slidable ice carriage shown generally at B. The frame A consists of a single supporting leg 1 at one end and two supporting legs 2 at the opposite end. Side rails 3 connect the legs at the upper end and each side rail has a cleat 4 secured to the outer face thereof for a purpose to be later described. A top 50 plate 5 is secured to the tops of the legs and is provided with transversely extending slots

6 as more particularly illustrated in Figure 4 of the drawings. The top plate 5 is preferably covered with metal as indicated at 7. A hopper 8 is secured beneath the plate 5 and under the transversely extending openings 6. Pointed rods 9 extend through the top plate 5 as more particularly illustrated in Figures 4 and 5 of the drawings and also extend over the transversely extending openings 6. 65 These pointed rods are arranged in rows as indicated in Figure 5.

The slidable ice carriage B comprises the side plates 10 having the vertically extending opening 11 therein for a purpose to be 70 later described. End plates 12 connect the ends of the side plates 10 and go forward with the side plates to make up a receptacle for receiving the ice to be shaved. A follower 13 is mounted in the vertically extending openings or slots 11 and is provided on the underface with a plurality of prongs 14. Rollers 15 are carried on the lower edge of the slidable ice carriage B and operate upon the upper edge of the cleat 4. A cleat 16 is 80 secured to the outer face of each side plate 10 and has a second cleat 17 hingedly connected thereto as indicated at 18. A plate 19 is secured to the lower edge of the plate 17 and is adapted to extend beneath the lower 85 edge of the cleat 4 when the carriage is in position. A turn button 20 is connected to the cleat 16 and adapted to extend over the cleat 17 as more particularly shown in Figure 1 of the drawings. 90

Cleats 21 are secured to the inner face of the legs 1 and 2 and carry a pan or tray 22 provided with a plurality of openings 23.

From the above detailed description it is thought that the operation and advantages 95 of my ice shaver will be clearly understood. The carriage B is secured upon the frame A by having the plate 19 extend beneath the cleat 4. The rollers 15 operate on top of the cleats 4 so that the carriage may be slid 100 backwards and forwards. The ice to be shaved is placed in the carriage with the follower 12 over the top thereof and the prongs 14 engaging in the ice. The ends of the follower may then be grasped and the carriage 105 may be moved over the top of the frame. This will bring the lower face of the ice in contact with the sharpened ends of the rods 9 and the ice will therefore be shaved and passed through the transversely extending 110 opening 6. The shaved ice will drop into the hopper 8 and be discharged into a bucket

or other suitable receptacle carried upon the pan or plate 22. Any water which may accumulate in the pan or plate 22 may be discharged out through the openings 23. If it is desired to remove the carriage the turn button 20 is operated so that the cleat 17 may be swung on the hinge 18. This will remove the plate 19 from beneath the cleat 4 and allow the carriage to be raised off of the frame. The foregoing description and the drawings have reference to what may be considered the preferred, or approved form of my invention. It is to be understood that I may make such changes in construction and arrangement and combination of parts, materials, dimensions, etc. as may prove expedient and fall within the scope of the appended claims.

Having thus fully described my invention, what I claim as new and desire to secure by Letters Patent, is:—

1. An ice shaver comprising a frame, shaving implements carried by the frame, cleats secured to the sides of the frame, a slideable

carriage, rollers carried by the carriage and adapted to operate on the upper face of the cleats, and means carried by the carriage for engaging the under face of the cleats.

2. An ice shaver comprising a frame, shaving implements carried by the frame, cleats secured to the sides of the frame, a slideable carriage, rollers secured to the carriage and operating on the upper face of the cleats, a cleat hingedly connected to the carriage, and a plate carried by the hinged cleat and adapted to engage under the cleat on the frame.

3. An ice shaver comprising a frame, shaving implements carried by the frame, cleats secured to the sides of the frame, a slideable carriage, and members hinged to the carriage for engaging the under faces of the cleats.

In testimony whereof I affix my signature in presence of two witnesses.

ANTONIOS J. MURZICOS.
